CHESTER A. FRICK, OF MUNCIE, INDIANA, ASSIGNOR TO GLASCOCK BROTHERS MANUFACTURING COMPANY, OF MUNCIE, INDIANA, A CORPORATION OF INDIANA.

CORRUGATING MACHINE.

Application filed May 1, 1925. Serial No. 27,153.

My invention relates to improvements in sheet metal bending machines and particularly to machines for forming corrugations or ridges in sheet metal.

5 My machine is adapted for forming a series of substantially semi-cylindrical indentations or ridges, in the sheet metal, extending from one edge to the other thereof, these semi-cylindrical indentations being 10 spaced apart by comparatively narrow peaks or ridges.

For the purpose of disclosing my invention I have illustrated one embodiment thereof in the accompanying drawings in 15 which—

Fig. 1 is a side elevation partly in section of a machine embodying my invention;

Fig. 2 is an end elevation thereof;

20 Fig. 3 is a bastard transverse section of a machine illustrated in Figs. 1 and 2.

Fig. 4 is a perspective view showing the center clamping member, and

Fig. 5 is a detail sectional view showing the action of the persuader bars.

25 In the embodiment of the invention illustrated I provide a suitable base member 1 which may be a solid casting and is mounted in any suitable manner as on risers 2. The top face of this base member is provided 30 with a plurality of semi-cylindrical dies 3 which extend the entire length of the bed or base 1 and are suitably spaced apart at 4. Co-operating with the dies 3 are a plurality of reciprocating dies 5 which are 35 adapted to be vertically moved toward the dies 3 and have their faces provided with quatra cylindrical recesses 6 adapted to coincide with the dies 3. There is provided a pair of the dies 5 for each of the dies 3 and 40 with the exception of the end dies the quatra cylindrical recesses 6 co-operate to form a projection adapted to extend into the space 4 between the dies 3. Each pair of dies 5 are separated on a line extending through 45 the center of a die 3. At each end, each of the dies 5 is provided with a riser 7 carrying on its face a roller 8 which roller co-operates with a cam bar 9 adapted to be projected transversely of the die bars and 50 engage beneath the rollers for the purpose

of raising the die bars 5 and holding the bars clear of the dies 3. This cam bar 9 slides on a shoulder 10 extending from a cross bar 11, one of which is provided at each end of the bed and mounted above the dies 5 and 3 being supported on one side by suitable spacer members 12 mounted on the side face of the bed 1 and on the opposite side by suitable supports or spacer members 13 likewise secured to a side face 60 of the bed. Each of the cam bars 9 on its under face is provided with a series of rack teeth 14 adapted to mesh in gears 15 mounted at opposite ends of a rotatable shaft 16. One end of this shaft is provided 65 with a driving gear 17 meshing with a driving pinion 18 operated by a suitable crank 19. By rotating the crank 19 in one direction the shaft 16 will be rotated and through the pinions or gears 15 project the cam bars 70 9 beneath the rollers 8 to successively raise the die bars 5 clear of the dies 3 to permit the insertion beneath the die bars 5 of the sheet to be corrugated. The die bars 5 are drawn down on the sheet to be corrugated by persuader bars which comprise a pair of spaced apart fulcrum bars 20 having hooked upper ends 21 adapted to engage over an end of a die bar 5 and set in a suitable recess formed transversely of the end of the die 80 bar. The lower ends of the fulcrum bars have pivotally mounted between the same on the pivot 22 a lever 23 eccentrically mounted on the pin 22 and having a cam edge 24 adapted to engage the under face of the bed 75 1 behind suitable lips 25. After the hooked ends 21 of the fulcrum bars 20 have engaged over the top of a die bar and with the free end of the lever 23 in a raised position and the cam end engaging behind the lip 25, it 90 is obvious that by drawing down on the lever the die bars at their ends will be forced downwardly upon the dies 3 thereby imparting the desired shape to the metal.

As the die bars 5 are comparatively long 95 and there is a tendency for these bars to bow at the center, in order therefore to insure accurate bending of the material throughout its entire length, I provide means for cramping the die bars 5 down at 100

their centers. To this end I provide three spaced apart pressure bars 26, 27 and 28 which are bridged across the top of the die bars 5 being supported upon and secured 5 to side members 29 secured to the side face of the bed 1. These bars are notched as at 30 on their under face and are spaced apart from the tops of the die bars 5. Co-operating with these bars is a pair of persuader 10 bars 31 having cam portions 32 at their lower end and transversely extending pins 33 which are adapted to engage in the notches 30. With the bars in their raised 15 position suitable spacer blocks 34 are inserted beneath the same on top of the die bar to be pinched down and by lowering the free end of the persuader bar 31 the cam end 32 engaging the spacer block 34 will cramp or pinch the center of the die bar 20 into position.

In operation the cam bars 9 are run under the rollers 8 of the various die bars until the die bars are all elevated a sufficient distance above the dies 3 to permit the insertion of 25 the sheet to be corrugated. After the sheet is inserted the two ends of the first die bar 5 (to the left looking at Fig. 2) are forced downwardly by means of the persuader bars and held in locked position. The center 30 portion is likewise crimped down by one of the persuader bars 31. With the persuader bars in locked position on the first die bar the next succeeding die bar is likewise forced down into position after which 35 the persuader bars on the first die bar may be removed and applied to the third die bar, thus successively moving a die bar downwardly and maintaining the next adjacent die bar in locked position so that the metal 40 of the sheet to be corrugated will be taken up from a free end.

I claim as my invention:

1. In a sheet metal corrugating machine 45 the combination with a plurality of spaced apart elongated dies substantially semi-cylindrical in cross section, of a plurality of co-operating dies having their faces recessed to form recesses corresponding to said first mentioned dies and means for moving 50 co-operating sets of dies forming a single corrugation successively to form the corrugations in the metal and holding each corrugating set of dies clamped upon the metal until the next succeeding set is being moved 55 to form a corrugation.

2. In a sheet metal corrugating machine 60 the combination with a plurality of spaced apart elongated dies substantially semi-cylindrical in cross section, elongated co-operating dies having recesses corresponding in shape to the cross sectional shape of said first mentioned dies, said recesses forming 65 projections adapted to engage between said first mentioned dies, means for moving said dies toward one another to form the corrugations

and for clamping each set of corrugating dies upon the metal until the next adjacent set is being operated to form a corrugation.

3. In a sheet metal corrugating machine 70 the combination with a plurality of die bars substantially semi-cylindrical in cross section and spaced apart from one another, a plurality of die bars adapted to co-operate with said first mentioned dies, said die bars 75 being formed in pairs having recesses on their faces, the recesses of a pair of dies forming a recess corresponding in cross sectional area to said first mentioned die bars and means for independently and successively moving said second mentioned die bars toward the first mentioned die bars and holding each of the second mentioned die bars in the position to which it has been moved until the next succeeding bar has 80 been moved to forming position.

4. In a sheet metal corrugating machine 85 the combination with a plurality of die bars substantially semi-cylindrical in cross section and spaced apart, a plurality of co-operating movable die bars each of which has a projecting portion for projection between the first mentioned die bars, the side faces of said projecting portion being curved to correspond to the curvature of the 90 first mentioned die bars and means for individually projecting the second mentioned die bars toward the first mentioned die bars to form the corrugations, and for clamping each set of die bars in position during the 95 projection of the adjacent set of die bars.

5. In a sheet metal corrugating machine 100 the combination with a plurality of stationary die bars spaced apart and substantially cylindrical in cross section, of a plurality 105 of movable die bars arranged adjacent one another each having a projection arranged to be projected between said stationary die bars, the side walls of said projection having a curvature corresponding to the curvature of said stationary die bars, means engaging the opposite ends of said movable die bars for projecting them individually toward the stationary die bars and means engaging said movable die bars intermediate 110 of the ends for forcing them toward the stationary die bars.

6. In a machine for corrugating sheet metal the combination with a plurality of die bars substantially semi-cylindrical in 115 cross section, of a plurality of reciprocable die bars having projections arranged to enter the space between said stationary die bars, the side faces of the projection having a curvature corresponding to the curvature 120 of said stationary die bars, means for simultaneously engaging the opposite ends of each of the die bars for elevating the same to separate the same from the stationary die bars, and means engaging the ends of 125 130

the movable die bars for independently projecting said die bars into engagement with the stationary die bars.

7. In a sheet metal corrugating machine, the combination with a plurality of stationary corrugating dies, of a plurality of relatively movable corrugating dies arranged to co-operate therewith each movable inde-

pendently of the other and means for successively moving each of the movable dies into co-operative relation with the stationary dies and for holding each movable die in said relation until the next succeeding die has been moved to co-operative relation with its stationary die.

CHESTER A. FRICK.
